UNITED STATES PATENT OFFICE.

ARCHIE M. BOVIER, OF ELMIRA, NEW YORK, ASSIGNOR TO AMERICAN SALES BOOK COMPANY, LIMITED, OF TORONTO, CANADA, A CORPORATION OF CANADA.

MANIFOLDING DEVICE.

1,173,551.

Specification of Letters Patent. Patented Feb. 29, 1916.

Application filed May 27, 1912. Serial No. 699,901.

To all whom it may concern:

Be it known that I, ARCHIE M. BOVIER, a citizen of the United States, residing at Elmira, in the county of Chemung and State 5 of New York, have invented certain new and useful Improvements in Manifolding Devices, of which the following is a full, clear, and exact description, such as will enable others skilled in the art to which it appertains to make and use the same.

This invention relates to manifolding devices, and with regard to certain more specific features thereof, to receptacles adapted to contain a suitable filler and the 15 upper surface of which forms a writing table.

One of the objects of the present invention is to provide a practical and compact device of the above character which will be 20 cheap to manufacture.

Another object is to provide a simple and self-contained device in which sets of record sheets may easily be inserted and subsequently used most conveniently.

25 A further object is to provide a device of the above character which will be durable in construction and efficient in use.

Other objects will be in part obvious and in part pointed out hereinafter.

30 In the accompanying drawing wherein is shown one of the various possible embodiments of this invention, Figure 1 is a perspective view of the complete device in operative position; and Fig. 2 is a sectional view 35 taken substantially along the line X—X of Fig. 1. Fig. 3 is a perspective view of a web as longitudinally folded for use in the receptacle and before being severed.

Similar reference characters refer to similar parts throughout the several views of 40 the drawing.

Referring now to the drawing and more particularly to Fig. 1, 3 denotes a receptacle 45 of any desired size, the upper surface 4 of which is inclined downwardly toward the front, thereby to provide a convenient surface for supporting the record sheets upon which the transactions are recorded. The receptacle 3 is mounted upon a revoluble pedestal 5, the base 6 of which is adapted to rest on the top of a counter or table. By having the receptacle revolvably mounted in this manner it can be conveniently and quickly turned from one side to the other as 55 when a salesman is in front of the counter

instead of in his usual position behind the counter. A cover 7 may be hinged or detachably secured to the rear side of the receptacle 3, if desired, whereby the device may be closed at night and locked by means 60 of a suitable snap-lock 8. The receptacle 3 contains a plurality of containers or drawers, two being shown in the present embodiment, 9 and 10, respectively. These drawers contain fillers which are preferably in the 65 form of a continuous web folded back and forth upon itself transversely, as shown in Figs. 2 and 3, and also longitudinally, forming several superimposed strips. The ends of these webs are passed through a slot 11 70 in the upper surface 4 of the receptacle where the longitudinally folded edges are engaged by diagonally disposed knife-blades 12 secured to the top of the receptacle. These knife-blades which are inclined as 75 clearly shown in Fig. 1, cut the folds and separate the web into a plurality of separate strips as the web is drawn through the slot 11.

As herein shown, the web 13 in the drawer 80 9 has but a single longitudinal fold so as to provide an original and duplicate strip. In this case only one knife-blade 12 is necessary, although two are shown in case it is desired to use a triplicate web as in 85 the drawer 10, where the filler 14 has two longitudinal folds, one at each side, thereby providing three record strips. A third drawer might be added if desired, in which a web of four or more strips is used. In 90 this manner any reasonable number of records of a single transaction may be obtained in a device of this character, according to which section of the device is used. For instance, in a cash transaction in which the 95 purchased article is taken away by the purchaser, a single copy may be all that is desired, while if the article is to be delivered, a third copy, to be sent to the delivery department, might be necessary.

100 After the webs have been separated into strips they are drawn down past guides 15 which keeps the lateral edges of the strips in alinement and thence under cutting edges 16 and 17, respectively, along the lower edge of the top of the receptacle. In order to produce manifold copies, suitable manifolding sheets are arranged above each of the lower strips. While a carbon coat 105 may be directly applied to the back of the 110

web if desired before being folded longitudinally, it is preferred to provide a roll of carbon paper 18 in a recess 19 in the upper surface of the receptacle. The carbon sheet is drawn across the path of travel of the web 13 and thence under the retaining and cutting edge 20 at the opposite side. If two copies of the transaction are desired, as when using the web 14, it is of course necessary to provide two strips of carbon paper, as shown, in the roll 21 which extends across the upper surface of the lower strips of the web 14. These carbon sheets are similarly retained by means of a cutting edge 22 on the receptacle.

The operation of this device is substantially as follows:—After removing the cover 7, the drawers 9 and 10 are pulled out and the fillers placed therein. The end of each 20 filler is then passed through the slot 11 so that it can be easily reached from above and the drawers returned to normal position. After starting the knives or blades 12 between the strips, they are pulled down- 25 wardly so that the webs are severed into a plurality of strips according to the number of longitudinal folds. After being drawn down to the lower edge of the table, the carbon sheets 18 or 20 are laid over the lower 30 strips and the original or top strips placed above the upper sheet as shown. The cutting edges or retaining means 16 or 17 are then clamped in position and the device is ready for use. After recording the 35 transaction the free ends of the strip are drawn outwardly and torn off along the cutting edge, thus producing a plurality of separated records of the transaction and the device is again ready for subsequent operations. As the carbon sheets become worn, 40 they are similarly drawn out through their retaining means and torn off.

As many changes could be made in the above construction and many apparently 45 widely different embodiments of this invention could be made without departing from the scope thereof, it is intended that all matter contained in the above description or shown in the accompanying drawings shall 50 be interpreted as illustrative and not in a limiting sense.

Having described my invention, what I claim as new and desire to secure by Letters Patent is:

55 1. In a manifolding device, in combination, a receptacle containing a plurality of webs, the upper surface of which is inclined downwardly toward the front, each web being folded back and forth upon itself longitudinally, means for cutting the web into 60 separate strips, guides for maintaining the lateral edges of said strips in alinement, manifolding sheets interposed between the strips, whereby a plurality of records of a transaction may be obtained, and means for 65

holding the free edges of said strips in position.

2. In a manifolding device, in combination, a receptacle containing a plurality of webs, the upper surface of which is inclined 70 downwardly toward the front, means for cutting each web into separate strips, guides for maintaining the lateral edges of said strips in alinement, a plurality of carbon sheets interposed between the strips, capable of being moved transversely to the movement of the strips, and means for holding the free edges of the strips and carbon sheets in place.

3. In a manifolding device, in combination, a receptacle containing a plurality of webs arranged side by side, the upper surface of which is inclined downwardly toward the front, each web being folded back and forth upon itself longitudinally, means 80 for cutting each web into separate strips, guides for maintaining the lateral edges of said strips in alinement, a plurality of carbon sheets interposed between the strips capable of being moved transversely to the 85 movement of the strips, and separate cutting edges for holding the free ends of the strips and carbon sheets in place.

4. In a manifolding device, in combination, a receptacle having an upper surface 90 and containing a plurality of longitudinally folded webs, the upper surface of said receptacle being inclined downwardly toward the front adapted to be used as a writing table, means for cutting the webs along their 95 longitudinal folds when withdrawn from the receptacle and laid over the upper surface thereof, said receptacle having recesses at the sides, and rolls of carbon paper in said recesses, the carbon paper arranged to 100 be drawn across the upper surface of the lower strips into which the webs are divided, whereby a plurality of records of a transaction may be obtained.

5. In a manifolding device, in combination, a receptacle having an upper surface and containing a plurality of longitudinally folded webs, the upper surface of said receptacle being adapted to be used as a writing table, means for cutting the webs along 110 their longitudinal folds when withdrawn from the receptacle and laid over the upper surface thereof, said receptacle having recesses at the sides, rolls of carbon paper in said recesses, the carbon paper arranged to 115 be drawn across the upper surface of the lower strips into which the webs are divided, whereby a plurality of records of a transaction may be obtained, and means pivotally supporting said receptacle whereby 120 the same may be conveniently turned around.

6. In a manifolding device, in combination, a receptacle having an upper surface containing a plurality of longitudinally folded webs, means for cutting the webs 125

along their longitudinal folds when withdrawn from the receptacle, rolls of carbon paper in said receptacle adapted to be drawn across the upper surface of the lower strips 5 into which the webs are divided, whereby a plurality of records of a transaction may be obtained, and means for holding the free ends of the carbon paper and the strips.

7. In a manifolding device, in combination, a receptacle having an upper surface and containing a plurality of longitudinally folded webs, the upper surface of said receptacle being inclined downwardly toward the front adapted to be used as a writing 10 table, means for cutting the webs along their longitudinal folds when withdrawn from the receptacle and laid over the upper surface thereof, rolls of carbon paper drawn across the upper surface of the lower strips into 15 which the webs are divided, whereby a plurality of records of a transaction may be obtained, cutting edges for holding the free ends of the strips of carbon paper in position, and means supporting said receptacle 20 whereby the same may be conveniently moved about.

8. In a manifolding device, in combination, a rectangular receptacle having a downwardly inclined upper surface adapted 30 to be used as a writing table, a plurality of removable drawers in said receptacle each containing a web folded back and forth upon itself transversely and longitudinally, said receptacle having an opening through 35 which the web may be drawn, cutter blades on the upper surface adapted to cut the web into separate strips, means for retaining the free edges of said strips in place, rolls of carbon paper positioned at the side of each 40 set of strips adapted to be laid in operative relation thereto, whereby a plurality of records of any transaction may be obtained, and means for holding said carbon paper in place.

45 9. In a manifolding device, in combination, a rectangular receptacle having a downwardly inclined upper surface adapted to be used as a writing table, a plurality of removable drawers in said receptacle 50 each containing a web folded back and forth upon itself transversely and longitudinally, said receptacle having an opening through which the web may be drawn, cutter blades mounted thereon adapted to cut the web 55 along its longitudinally folded lines into separate strips, means for retaining the free edges of said strips in place, rolls of carbon paper positioned at the side of each set of strips, the paper laid in operative relation 60 thereto, whereby a plurality of records of any transaction may be obtained, means for holding said carbon paper in place, a cover

for said receptacle, and means for locking the cover in closed position.

10. In a manifolding device, in combination, 65 a rectangular receptacle having a downwardly inclined upper surface adapted to be used as a writing table, a plurality of drawers in said receptacle each containing a web folded back and forth upon itself 70 longitudinally, cutter blades on the upper surface cutting the web along its folded lines into separate strips, means for retaining the free edges of said strips in place, rolls of carbon paper at the side of each 75 set of strips, the paper laid in operative relation thereto, whereby a plurality of records of any transaction may be obtained, means for holding said carbon paper in place, a cover for said receptacle, means for 80 locking the cover in closed position, and means for supporting said receptacle whereby the same may be conveniently moved about.

11. In a manifolding device, in combination, 85 a rectangular receptacle, a plurality of drawers in said receptacle each containing a web folded back and forth upon itself longitudinally, said receptacle having an opening through which the web may be drawn, 90 cutter blades on the upper surface cutting the web along its folded lines into separate strips, means for retaining the free edges of said strips in place, rolls of carbon paper at the side of each set of strips, the paper laid 95 in operative relation thereto, whereby a plurality of records of any transaction may be obtained, means for holding said carbon paper in place, a cover for said receptacle, means for locking the cover in closed position, 100 a base and a pivotal connection between the base and the receptacle whereby the receptacle may be rotated about said base.

12. In a manifolding device, in combination, 105 a receptacle comprising a drawer and a top forming a web supporting surface, a web therein folded along longitudinal lines, said top having a slot through which a web may pass from said drawer, a cutting edge disposed transversely over the path of 110 said web near an edge of said top, a cutter for severing said web along longitudinal lines as it is drawn over said top past said cutting edge, said top having a recess containing a supply of manifolding sheet, and 115 a manifolding sheet retainer against which the manifolding sheet may be torn.

In testimony whereof I affix my signature, in the presence of two witnesses.
